CHICKEN COOP

Daniel C. Wedrich, Concordia, Mo.

Application July 25, 1933, Serial No. 682,121

1 Claim. (Cl. 217—36)

This invention relates to chicken coops and one object of the invention is to provide a coop which will be very strong in its construction and can be subjected to rough handling without liability of 5 being broken.

Another object of the invention is to construct a coop in which rods or bars extending between marginal strips of the coop are formed of metal to prevent them from easily snapping and to so 10 mount them in the marginal strips that they will be firmly mounted and prevented from accidentally slipping out of place or being deliberately worked loose.

Another object of the invention is to provide a 15 coop having a solid bottom which not only adds strength to the coop but also prevents the feet of chickens in the coop from passing through the bottom and permits grain and other feed to be placed in the coop.

20 The invention is illustrated in the accompanying drawing wherein.

Figure 1 is a perspective view of the improved coop.

Figure 2 is a perspective view of a corner portion of the crate with portions of the marginal strips broken away to illustrate the manner in 25 which the rods are mounted.

Figure 3 is a perspective view of the door in the top of the crate.

30 This improved crate which is to be used for confining chickens, and other fowls may be of any dimensions desired according to the number and size of fowls to be confined therein and has a bottom 1, side and end walls 2 and 3 and top 4. The 35 bottom is formed of tongue and groove boards 5 as shown in Fig. 1 in order to provide a solid floor or bottom for the crate and permit the fowls to walk easily in the crate and also permit food to be placed therein for consumption by the fowls.

40 This also adds strength to the crate and permits them to be stacked one upon another.

In order to form the side and end walls there has been provided corner posts or standards 6 which rise from the bottom and there has also 45 been provided upper and lower bars or rails 7 and 8 which may be referred to as marginal strips for the crate. These strips and the standards are preferably 1 inch thick by 2 inches wide and formed of wood but it is to be understood that the 50 dimensions can be varied if found advisable. In order to secure the strips 7 and 8 to the corner posts bolts 9 are used and it should be noted that the bolts are so passed through the posts that while they extend through the same at right angles to each other and cross each other through 55

the posts they will be located one above another. This prevents the bolts from interfering with each other and also prevents undue weakening of the posts. After the marginal strips have been secured, metal plates 10 are applied at corners 60 of the bottom to reinforce them and prevent damage if a crate is carelessly handled and dropped. Rods or bars 11 extend vertically between the upper and lower strips, and these rods are formed of strong metal and have their end portions seated 65 in sockets formed in the marginal strips as shown in Fig. 2. Referring to this figure it will be seen that the rods are firmly embedded in the strips and when the strips are secured to the corner posts can not slip out of place or be slid longitudinally to such a position that they can be removed. They also serve very effectively as braces to prevent the corner posts from being broken by longitudinal or transverse strain.

The top 4 is also formed of wooden strips and 70 metal rods and has end strips 12 and intermediate strips 13 spaced from each other longitudinally of the crate and formed with side sockets to receive the metal rods 14. The rods back of the door 15 may extend the full length of the 75 crate and pass through the intermediate strips 13 or they may be in sections each having its ends embedded in strips. The end strips are nailed to the upper marginal strips of the end walls and between the intermediate strips is mounted a 80 cross bar or strip 16 to which the door is connected by hinges 17.

85 Referring to Figure 3 it will be seen that the door consists of side and end strips 18 and 19, the end strips being recessed as shown at 20 to 90 receive ends of the side strips which are secured by nails 21 and braced against movement towards each other by portions of the end strips which extend between them. Sockets are formed in inner side faces of the end strips to receive end 95 portions of rods 22 corresponding to the rods 11 and 14 and in order to secure the door closed there has been provided a hasp 23 carried by the front strip of the door and engageable with a companion element 24 carried by the upper marginal strip of the front wall of the crate which may be a suitable latch or a staple to receive a padlock after the door has been closed and the hasp moved into engagement with the keeper 24. The door when closed fits snugly between the intermediate strips 13 and will therefore be braced against side strain and be prevented from being 100 wrenched loose from the strip 16.

105 When this crate is in use the door is opened and chickens or other fowls thrust through the 110

same into the crate. The door is then closed and its hasp secured to hold the door shut and prevent escape of the fowls by the door accidentally opening. The fowls can walk easily upon the solid bottom of the crate and also corn and other feed may be placed in the crate for consumption by the fowls. The crate is strongly made and not liable to be broken if roughly handled and also the rods will not easily snap or work loose. 10 A very efficient crate has therefore been produced.

What is claimed as new is:—

A crate comprising a bottom, side and end

walls rising from said bottom and having upper and lower marginal strips, a top for said crate having end strips secured upon upper strips of the end wall and intermediate strips fixed to said walls, a cross bar extending longitudinally of 80 said crate between the intermediate strips, metallic rods extending longitudinally of said top and anchored in the end strips, a door hinged to said cross bar and fitting snugly between the intermediate strips when closed, one side bar of 85 the door resting upon and engaging the top of one side wall of the crate.
